UNITED STATES PATENT OFFICE.

HENRY STRAUSS, OF CHEMNITZ, GERMANY.

INK BLOTTER.

Application filed March 9, 1922. Serial No. 542,522.

To all whom it may concern:

Be it known that I, HENRY STRAUSS, a citizen of the German Republic, residing at Chemnitz, Germany, have invented certain new and useful Improvements in Ink Blotters (for which I have filed applications in Germany March 26, 1921, and May 21, 1921), of which the following is a specification.

10 In the usual screwless blotters the block of sheets of blotting paper is secured in its position upon the blotter simply by clamping in. The part which carries the block of sheets of blotting paper must either be 15 composed of two parts which may be hingedly connected the one with the other or, if the support is made in one part only, strong layers of sheets of blotting paper cannot be securely fixed and the attachment 20 must be regulated in any case if the pile of sheets of blotting paper gets thinner. In most cases only a small number of sheets of blotting paper can be mounted upon a plate and clamped in by the bent, or rolled ends of 25 the plate.

According to this invention the block of sheets of blotting paper is fixed upon a support, preferably made of card-board and sold in this state. The blotter, upon which 30 the block of sheets of blotting paper is fixed, serves merely for holding the said support. The support for the block of sheets of blotting paper has slotted ends which are inserted between the upper and lower part of 35 the blotter proper and transversed by large flaps of the upper part.

The block of sheets of blotting paper can be of any convenient thickness as not the blotting paper itself but merely its support 40 is clamped in.

In order that the invention may be clearly understood, I shall proceed to describe the same with reference to the form of construction shown, by way of example, on the 45 accompanying drawing, wherein:

Fig. 1 shows the improved blotter in front elevation, partly in cross section.

Fig. 2 is a plan view of the same.

Fig. 3 illustrates the block of sheets of 50 blotting paper.

The blotter is made of sheet metal and composed of an upper part *a* of the usual curved shape and of a lower part *d*. A flap *b*, *c* respectively, is cut out at each end of

the upper part *a* and bent inwardly. The 55 lower part *d* which is curved in opposite direction as the upper part has its ends *e*, *m* bent upwardly so that they adapt themselves to the curvature of the upper part *a*, slits *f*, *g* being provided in these ends *m*, *e* 60 which serve for the reception of the flaps *b* and *c* of the upper part.

The flaps *b*, *c* are securely held in the slits of the lower part by the elasticity of the upper part *a* so that a strong pull is 65 necessary to separate the upper part from the lower part. The block *i* of sheets of blotting paper is attached to a strip *h* of card board the ends *k*, *l* of which are bent upward and have slits which correspond 70 with the slits in the ends of the lower part *d*. The card board support *h* of the block of sheets of blotting paper *i* is placed upon the outer surface of the lower part *d* so that the ends *k*, *l* of the card board support extend over the upwardly bent ends *e*, *m* of 75 the lower part of the blotter, whereupon first one of the flaps *b*, *c* of the upper part *a* is pushed through the corresponding registering slits of the card board support and 80 of the upwardly turned end *e* or *m* of the lower part, the other flap of the upper part being then pushed through the slits of the other upwardly extending ends of the lower part *d* and of the card board support *h*, 85 whereby a secure and very simple connection is obtained.

This blotter is very easy to manufacture as the upper part as well as the lower part consists each only of one stamped and 90 curved piece of sheet metal. Upon the upper surface of the card board support *h* advertisements are printed and the lower part *d* of the blotter has a window *n* through which the advertisement *o* can be 95 seen as shown on Figure 3.

I claim:

An improved ink blotter comprising in combination an upper curved part of sheet metal, inwardly bent flaps cut out of the 100 ends of said upper part, a lower part of sheet metal curved in opposite direction as said upper part having a large opening (window), upwardly bent ends of said lower part having slits designed to receive the 105 flaps of the upper part, a block of sheets of blotting paper, a card board support upon which said block of sheets of blotting

paper is fixed having advertisements upon its free surface, and laterally projecting ends of said card board support having slits designed to register with the slits of the lower part and to receive the flaps of the support, substantially as described and shown and for the purpose set forth.

In testimony whereof I affix my signature in presence of two witnesses.

HENRY STRAUSS.
